UNITED STATES PATENT OFFICE.

JOHN C. SIGLER AND ROY G. SIGLER, OF CHICAGO, ILLINOIS.

DESIGN FOR A CASING FOR A DIRECTION-INDICATING DEVICE.

Application filed April 13, 1929. Serial No. 30,893. Term of patent 3½ years.

To all whom it may concern:

Be it known that we, JOHN C. SIGLER and ROY G. SIGLER, citizens of the United States, residing at Chicago, in the county of Cook and State of Illinois, have jointly invented a new, original, and ornamental Design for a Casing for a Direction-Indicating Device, of which the following is a specification, reference being had to the accompanying drawing, forming a part thereof.

Fig. 1 is a top plan view of the casing for a direction indicating device;

Fig. 2 is a front view in elevation; and

Fig. 3 is an end view elevation of the device.

We claim:

The ornamental design for a casing for a direction indicating device, as shown.

JOHN C. SIGLER.

ROY G. SIGLER.
